FIG. 1.

Des. 212,018

PAGE 2

FIG. 3.

FIGURE 1 is a front perspective view of a child's combination multiple climber and slide or similar article, showing our new design;

FIGURE 2 is a rear perspective view of FIGURE 1 wherein the conventional slide tube supports are eliminated for convenience of illustration; and

FIGURE 3 is a front perspective view of a modified form of FIGURE 1 wherein bars are substituted for the solid plates above the slide tubes.

The dotted-line showings in FIGS. 1 and 3 show conventional support members.

We claim:

The ornamental design for a child's combination multiple climber and slide or similar article, as shown.
